Patented November 17, 1903.

UNITED STATES PATENT OFFICE.

WALTER TURTON, OF ARLINGTON, NEW JERSEY, ASSIGNOR TO EVAN H. EASTWOOD, CHARLES W. PARK, AND EDWARD SICKLES, OF NEWARK, NEW JERSEY, COPARTNERS TRADING AS EASTWOOD AND PARK.

DESIGN FOR A BACK FOR MIRRORS, BRUSHES, OR SIMILAR ARTICLES.

SPECIFICATION forming part of Design No. 36,627, dated November 17, 1903.

Application filed October 24, 1903. Serial No. 178,448. Term of patent 3½ years.

To all whom it may concern:

Be it known that I, WALTER TURTON, a subject of His Majesty the King of Great Britain, and a resident of Arlington, in the county of Hudson and State of New Jersey, have invented a certain new, original, and ornamental Design for a Back for Mirrors, Brushes, or Similar Articles, which is illustrated in the accompanying drawing, forming part of this specification.

The design is executed in relief.

What I claim is—

The ornamental design for the back of a mirror, brush or similar article, as shown.

Signed at Newark, in the county of Essex 15 and State of New Jersey, this 21st day of October, A. D. 1903.

WALTER TURTON.
